(57) **CLAIM**

The ornamental design for a combined ceiling fan and light fixture housing, as shown and described.

DESCRIPTION

FIG. 1 is a bottom perspective view of a combined ceiling fan and light fixture housing showing an embodiment in accordance with my design;

FIG. 2 is a reduced top plan view of the combined ceiling fan and light fixture housing in accordance with my design;

FIG. 3 is a reduced bottom plan view of the combined ceiling fan and light fixture housing in accordance with my design; and,

FIG. 4 is an enlarged side elevation view of the combined ceiling fan and light fixture housing in accordance with my design, all sides being substantially identical.

The broken line showing of a canopy, blades and a support rod is included for the purpose of illustrating environmental structure and forms no part of the claimed design.
